Primary Examiner — Ricky Pham

(57) **CLAIM**

The ornamental design for a spoon, as shown and described.

DESCRIPTION

FIG. 1 is a front top perspective view of a first embodiment of a spoon;

FIG. 2 is a bottom perspective view of the spoon of FIG. 1; FIG. 3 is a right side elevation view of the spoon of FIG. 1; FIG. 4 is a left side elevation view of the spoon of FIG. 1; FIG. 5 is a rear elevation view of the spoon of FIG. 1; FIG. 6 is a front elevation view of the spoon of FIG. 1; FIG. 7 is a top plan view of the spoon of FIG. 1; FIG. 8 is a bottom plan view of the spoon of FIG. 1; FIG. 9 is a front top perspective view of a second embodiment of a spoon;

FIG. 10 is a bottom perspective view of the spoon of FIG. 9;

FIG. 11 is a right side elevation view of the spoon of FIG. 9;

FIG. 12 is a left side elevation view of the spoon of FIG. 9; FIG. 13 is a rear elevation view of the spoon of FIG. 9; FIG. 14 is a front elevation view of the spoon of FIG. 9; FIG. 15 is a top plan view of the spoon of FIG. 9; and, FIG. 16 is a bottom plan view of the spoon of FIG. 9.

The broken lines in the drawings represent portions of the structure that form no part of the claimed design.

1 Claim, 10 Drawing Sheets
